United States Patent Office

Des. 187,082

Patented Jan. 19, 1960

187,082

WALL LIGHTING FIXTURE OR THE LIKE

William M. Parker, Jr., deceased, late of Union District, W. Va., by Edith M. Parker, executrix, Union District, W. Va., assignor to Union Insulating Co., Inc., Parkersburg, W. Va., a corporation of West Virginia

Application July 15, 1959, Serial No. 56,794

Term of patent 14 years

(Cl. D48—4)

Fig. 1 is a front view of a wall lighting fixture or the like showing the new design.

Fig. 2 is a side elevational view thereof.

Fig. 3 is a rear elevational view thereof with the wires fragmentarily shown for convenience of illustration.

Fig. 4 is a top plan view thereof.

Fig. 5 is a bottom plan view thereof.

What is claimed is:

The ornamental design for a wall lighting fixture or the like, as shown.
